UNITED STATES PATENT OFFICE.

JACQUES AUGUSTIN NORMAND, FRANCOISE ELISABETH NORMAND, MARIE EMILIE NORMAND, AND PIERRE SIGAUDY, OF HAVRE, FRANCE.

FEED-WATER DEVICE FOR STEAM-GENERATORS.

SPECIFICATION forming part of Letters Patent No. 593,115, dated November 2, 1897.

Application filed September 12, 1896. Serial No. 605,661. (No model.) Patented in Belgium August 4, 1896, No. 122,862; in England August 5, 1896, No. 17,309; in Austria August 30, 1896, No. 3,347; in Denmark May 22, 1897, No. 1,098, and in Italy September 23, 1897, No. 49.

To all whom it may concern:

Be it known that we, JACQUES AUGUSTIN NORMAND, FRANCOISE ELISABETH NORMAND, MARIE EMILIE NORMAND, and PIERRE SIGAUDY, citizens of France, and residents of Havre, in the Department of the Seine-Inférieure, France, have invented a new and useful Improvement in Feed-Water Devices for Steam-Generators, (for which we have obtained Letters Patent in England, No. 17,309, dated August 5, 1896; in Austria, No. 3,347, dated August 30, 1896; in Belgium, No. 122,862, dated August 4, 1896; in Denmark, No. 1,098, dated May 22, 1897, and in Italy, No. 49, dated September 23, 1897,) of which the following is a specification.

When the amount of steam generated in a boiler is considerable relatively to the evaporation-surface and when the feed-water has to be divided between a number of boilers, it is desirable to regulate the admission of such feed-water automatically, and the apparatus for this purpose should combine the following features, viz: First, the operation of the apparatus should be very reliable, since when an automatic apparatus is employed the firemen will not watch the water-gages so closely as they would do if such apparatus were not provided. The apparatus should therefore be sufficiently powerful to actuate the distributing-gearing with certainty, and it should be in a position such as to enable the efficiency of its operation to be tested at any time, and, second, when used in connection with marine boilers the apparatus should be as independent as possible of the changes of level of water in the boiler, owing to the motion of the vessel.

In the accompanying drawings, Figure 1 is a vertical section of the improved apparatus. Fig. 2 is another vertical section thereof, taken on the line X X'. Fig. 3 is a plan of the apparatus with the cover removed. Fig. 4 is a vertical section of the apparatus, taken on the line Y Y'; and Fig. 5 is a horizontal section, taken on the line Z Z', of the part of the apparatus wherein the feed-regulating cylindrical slide-valve E moves.

The apparatus consists of a chamber or reservoir A, in which is a float B, balanced

by a counterweight C, to which it is connected by the beam D. When the chamber A is filled with water, the float B is in its highest position, as shown in the drawings; but when the said chamber A is empty the float B descends to its lowest position. When the said chamber A is partially filled with water, the said float B takes up intermediate positions.

The slide-valve E is connected to the float B and therefore is raised and lowered with the said float, altering, according to its position, the section of feed-water inlet in the boiler.

There is a central perforation e through the axis of the valve E, so that pressure in the valve-casing beneath the valve and in the chamber A is the same. The feed-water enters at F and issues at G on its way to the boiler.

The apparatus is preferably placed above the normal level in the boiler, to which it is fitted at such a height that the discharge-pipe H from the vessel A is inclined downward gradually to its extremity I, which opens at or about the normal level of the water in the boiler, and is horizontally near the center of the evaporation-surface of the water, which center is independent of the motion of the vessel. The diameter of this pipe should be large enough to afford a passage simultaneously to the water that is discharged and to the steam that takes its place. Instead of a single pipe there may be two such pipes, one for water, secured to the lower part of the vessel A, and the other for steam, this latter pipe being of much smaller diameter than that for water, and being secured to the upper part of the said vessel, the lower orifices of both pipes being at the same height at or near the normal level of the water in the boiler. It will be assumed in the following description that a single pipe is used. At the top the chamber A also communicates through a very small orifice in the cock J with a space or chamber wherein the pressure is less than that prevailing in the boiler—such, for example, as a feed-water heater constructed upon Normand's system—the intermediate receivers between the cylinders, the cold-water cistern, or the condenser, or even the atmos-

phere itself. The pressure within the chamber A therefore is always somewhat less than the pressure in the boiler, and a constant flow of water and steam is created between the 5 boiler and the chamber A.

The operation is as follows: If the water-level in the boiler rises above the orifice I of the pipe H, the chamber A becomes filled with water, owing to the partial vacuum produced 10 by the escape of steam or water through the small orifice in the cock J, (for which one to four square millimeters will be a sufficient sectional area.) The valve E rises and closes 15 and only allows the feed-water to pass through a narrow orifice K. As the water-level sinks in the boiler, owing to insufficient feeding, it eventually uncovers the orifice I of the pipe H. The water then leaves the chamber A, the 20 float B and valve E descend, and the passage for the feed-water supply to the boiler is opened.

The water-level in the boiler around the orifice I of the pipe H is preserved from injurious fluctuation or disturbance, due to the 25 rising of steam-bubbles or to the motion of the vessel, by means of a chamber or space L, closed on all sides and only communicating with the volume of water contained in the boiler through the orifice M, situated at 30 its lower part.

The apparatus is secured to the boiler by means of a cock N. The closing of the cocks N and J enables the apparatus to be isolated when required.

35 A rod P, connected to the counterpoise-weight C, serves to indicate the movement of the several movable parts and enables them to be operated either directly by hand or through the medium of a lever or the like 40 whenever it is required either to insure the proper operation of those parts or to increase the feed-water supply in an emergency. The rod P should be of small diameter, and its packing in the stuffing-box should offer only 45 such a minimum resistance to motion as is absolutely necessary to insure tightness. The said rod P may be dispensed with where it is found to involve too great a sacrifice of the sensitiveness of the apparatus, or the effect 50 of the friction between the rod P and its stuffing-box may be counteracted by increasing the weight of the counterpoise C and reducing the length of the arm of the beam or lever D, from which it is suspended.

55 The apparatus will act in a satisfactory manner with somewhat considerable variation in the level or height of the orifice I of the pipe H in relation to the normal water-level in the boiler; but herein is given what 60 we consider the most favorable conditions and those under which the apparatus will give the best results if applied to each constituent boiler of a battery of boilers, all fed from one and the same feed-water supply. It is well 65 known that in a battery of this class the feed-water is the more evenly divided the narrower

the sectional area of the orifice through which such water is discharged into the boiler, for there is such an increase of pressure between the feed-pipes and the boilers that the discharge takes place almost uniformly in all, whatever may be the slight differences of pressure between the different boilers and the want of symmetry between the connections of the several boilers with the feed-water 70 collecting-pipe. The production of steam in all the boilers, however, is not the same, and the possible want of symmetry of the steam-valves in relation to the steam-collecting pipe 75 considerably increases the difference of production. The object of the feed-regulator is to remedy this cause of instability of the water-levels.

Supposing now that the orifices I of the pipes H in the several boilers of the battery 80 are arranged uniformly somewhat beneath the normal level, generally the feed-regulators are filled with water, the slide-valves are closed, and the boilers are fed solely through a supply-orifice of a very small sectional area. 85 There is therefore a greater or lesser excess of pressure, say, from one to three atmospheres, 90 between the feed-water supply and the boilers, and there are the conditions above referred to upon which depends as uniform a 95 division of the feed-water as possible between the several boilers of the battery. When the water-level in any one of the boilers descends below the orifice I of the pipe H, the feed-water regulator of such boiler is evacuated, 100 the float in descending opens the slide-valve, the discharge-port of which becomes four, five, or six times larger, for example, than it was when the slide-valve was closed, and accordingly the amount of water fed to that 105 boiler becomes four, five, or six times greater than in the other boilers. The water-level rises the more rapidly the greater this proportion of ratio, and the moment it attains the orifice I of the pipe H the chamber of the 110 apparatus is filled with water and the slide-valve closed. Now assuming, on the other hand, that the orifice I of the said pipe H is situated somewhat above the normal level of the boilers, the feed-regulators are then generally empty, and the difference of pressure 115 between the feed-water supply and the boilers will therefore be very slight, which is a rather unfavorable condition, as before stated, for the equal division of the feed-water among 120 the several boilers of the battery. The level may sink rapidly in a boiler without causing any change to take place in the feed-water supply, since the feed-regulator only acts when the water-level rises, while previously 125 its operation was brought about by the descent of the water-level. Now it will be understood that it is far more desirable that the feed-regulator should resist or counteract an abnormal lowering of the water-level than an abnormal rising of the same. When the level rises in any one boiler of the battery above 130

the orifice I of the pipe H, the feed-regulator becomes filled, the cylindrical slide-valve closes, owing to the rising of the float, and the amount of feed-water admitted to that 5 boiler is in consequence considerably reduced in comparison to what it is in the remaining boilers of the battery. Again, if the orifice I of the pipe H be at the same height as the normal level, the inconveniences attaching 10 to the arrangement previously described are to a great extent remedied, although the conditions are still less favorable than they were in the arrangement first described—that is to say, the arrangement wherein the orifice referred 15 to is situated somewhat below the normal level.

In short, if stability of level be taken to mean the greater or less rapidity with which such level is restored to its normal height when it 20 happens to be lowered, such stability will be far greater when the orifice I of the pipe H is situated a little distance below the normal level than when it is arranged above that level.

In view of the foregoing statements it will 25 be readily understood that the feed-regulator, according to this invention, complies with the conditions laid down as being those upon which the proper operation of all feed-regulators depends. It is sufficiently powerful to 30 properly set the distributing or valve gearing in operation, inasmuch as it acts in virtue of the total weight of the water displaced by the float, whereas in the majority of existing feed-water regulators a fraction only of the volume 35 of the float becomes the determining cause of the motion and a considerable change of level is necessary to produce an appreciable amount of power. In the apparatus according to this invention, however, the slightest 40 change of level is sufficient to set in operation or give effect to the maximum power as applied to the operation of the distributing-gearing.

The improved apparatus may at any time 45 be disconnected from the boiler and tested. The orifice I of the pipe H being situated in the vicinity of the center of the evaporating-surface, the level of the water in that portion of the apparatus is independent of any of the 50 movements of the vessel on which the feed-regulator is employed. Besides, this apparatus enables a feed-pump common to a number of boilers to be employed, a circumstance which affords very material advantages, 55 admitting, as it does, of the mechanism being greatly simplified and of a considerable amount of fuel being saved.

The feed-regulator will also operate satisfactorily if placed below the water-level. In 60 this case the escape-cock should be placed in the lower part of the reservoir and the water discharged, substituted by steam or water, as the case may be, all of which takes place under the same conditions as before.

65 There are already a number of arrangements in existence which cause feed-water to

be supplied to boilers by means of a pipe similar to the pipe H, opening in the vicinity of the normal water-level of the boiler, but in all these the motor fluid, whether water or steam, acts upon a special feeding device, whereas in the apparatus forming the subject of this invention the motor fluid, whether water or steam, merely modifies the sectional area of the feed-water-supply orifice in each 70 constituent boiler of a series or battery, such feed-water being supplied from a perfectly independent feeder.

It will be understood that the proportions, dimensions, and accessory devices may vary 80 according to requirements without departing from the principle of the invention.

Having now particularly described and ascertained the nature of the said invention and in what manner the same is to be performed, 85 we declare that what we claim is—

1. A feed-water regulator consisting of an exterior float-chamber having a small outlet at the top, a pipe communicating with the lower part of said float-chamber and inclined 90 from the latter to the discharge end which is within the boiler and at, or near, the normal water-level, a valve-chamber communicating with the float-chamber and boiler, a valve arranged in said valve-chamber and provided 95 with a small passage to equalize the pressure beneath the valve and in the float-chamber, a feed-water pipe communicating with the boiler through said valve-chamber, a float arranged in the float-chamber and connected 100 to the valve-stem, and a counterbalance for said float, substantially as described.

2. In a feed-water regulator, the combination with a boiler of an exterior float-chamber having a small outlet-cock at top to discharge into a space having a less pressure than that in the chamber, a valve-chamber entering the lower part of the float-chamber, a feed-water pipe communicating with said valve-chamber and with the boiler, a valve in 110 said valve-chamber having a small channel to equalize the pressure beneath the valve and in said float-chamber, a counterbalanced float in said float-chamber connected to the valve-stem, and a pipe communicating with 115 the float-chamber and with the interior of the boiler, its lower end being at or near the normal water-level, substantially as described.

3. In a feed-water regulator, the combination with a boiler of an exterior float-chamber having a small outlet at top, a valve-chamber communicating with the lower part of said chamber, a feed-water pipe communicating with the boiler through the valve-chamber, a pipe communicating with the float-chamber and having its discharge end at or 120 near the normal water-level and within a space inclosed upon all sides except a contracted orifice at the bottom, a valve in the valve-chamber to regulate the area of the 125 feed-water inlet to the boiler, said valve having a small channel for the passage of water,

or steam, a float in the float-chamber connected to the stem of said valve, and a counterbalancing-weight for said float having a rod which is packed through the lower wall of the chamber and provided upon its exterior end with means for operating the float and its connected valve manually, substantially as described.

In testimony whereof we have signed this

specification in the presence of two subscr-
ing witnesses.
